UNITED STATES PATENT OFFICE.

FRANK M. NEVINS, OF COALINGA, CALIFORNIA.

SUCKER ROD.

Application filed March 6, 1924, Serial No. 697,816. Renewed March 9, 1926.

My invention relates to improvements in sucker rods for deep wells, and has reference more particularly to rods of the tubular type, adapted to contain air whereby they are rendered buoyant and consequently greatly facilitate the operation of the pump with which connected. I am aware that a tubular sucker rod has been devised to contain compressed air to counteract the external pressure of the liquid in which the rod operates and to impart buoyancy to said rod, but whereas it is necessary to compress the air in the tubular rod to which I refer, by means of an air compressor or the like, it is the object of my invention to provide a tubular rod which is open at its lower end to permit the liquid from the well to rise to some extent in the rod, so that such liquid will compress the normal atmospheric air in said rod and will consequently produce an internal pressure in the rod, equal to the external pressure.

With the foregoing in view, the invention resides in the novel subject matter herein-after described and claimed, the description being supplemented by the accompanying drawing.

Figures 1 and 2 are side elevations partly in section, showing a section of a sucker rod constructed in accordance with my invention.

Figure 3 is an enlarged vertical sectional view as indicated by line 3—3 of Fig. 2.

Figure 4 is a sectional view at right angles to Fig. 3 as indicated by line 4—4 thereof.

Figures 5 and 6 are horizontal sections as indicated by lines 5—5 and 6—6 of Fig. 3.

In the drawing above briefly described, the numeral 1 designates a section of a sucker rod constructed in accordance with my invention, said section being in the form of a metal tube of any desired dimension, the upper and lower ends 2 and 3 of said tube being preferably contracted and integrally joined to squared necks 4 for engagement with a wrench, one of these necks being provided with a socket 5 while the other is equipped with a threaded nipple 6, so that the tubular rod section may be

coupled to other sections, whether of ordinary construction or of tubular form.

I have shown all parts of the tube 1, except its lower extremity, of air-tight construction, but have illustrated a pair of 55 openings 7 in said lower extremity so that liquid from the well may enter the tube and compress the atmospheric air in the latter, thereby imparting buoyancy to the rod and counteracting the inward pressure of the 60 liquid upon the tube. If desired, only one opening might be employed, or any desired number of such openings may be used, as occasion may require. Each opening is preferably covered with a screen 8 to prevent 65 sand and the like from entering the rod.

To protect the rod against contact with a crooked well casing, I preferably provide collars 9 which are preferably shrunk around the rod at suitable points, said collars being provided with liquid passages from top to bottom, which are preferably in the form of transverse grooves 10 in the peripheries of said collars.

By providing the construction shown and described, or a substantial equivalent thereof, a very desirable and efficient rod is produced and as excellent results may be obtained from the details disclosed, they are preferably followed, but within the scope of 80 the invention as claimed, numerous minor changes may be made.

I claim:

1. A sucker rod comprising a tube closed at its upper end but open at its lower end 85 to admit liquid from the well in which the rod is used whereby such liquid may compress air in the tube to counteract the inward pressure of the liquid and impart buoyancy to the rod. 90

2. A sucker rod comprising a tube closed at its upper end but having a screened opening in its lower end to admit liquid from the well in which the rod is used, whereby such liquid may compress air in the tube to 95 counteract the inward pressure of the liquid and impart buoyancy to the rod.

In testimony whereof I have hereunto set my hand.

FRANK M. NEVINS.
